Seymour Nesbit, 2245 Guthrie Circle, Los Angeles, Calif.

Filed Dec. 24, 1959, Ser. No. 58,817

Term of patent 3½ years

(Cl. D7—7)

FIG. 1.

FIG. 2.

FIG. 3.

FIG. 4.

The dominant features of my design reside in the portions shown in full lines and consist of the sequin and bugle bead ornamentation applied to the outer surface as shown.

I claim:

The ornamental design for a slipper, substantially as shown and described.
